UNITED STATES PATENT OFFICE.

CLIFFORD C. YOUNG, OF DES MOINES, IOWA.

VALVE-SPRING LIFTER.

Application filed March 30, 1922. Serial No. 543,097.

To all whom it may concern:

Be it known that I, CLIFFORD C. YOUNG, a citizen of the United States, and a resident of Des Moines, in the county of Polk 5 and State of Iowa, have invented a certain new and useful Valve-Spring Lifter, of which the following is a specification.

The object of my invention is to provide a valve spring lifter of simple, durable and 10 inexpensive construction.

A further object of my invention is to provide a device of the kind mentioned having a forked end adapted to rest on the engine block of a Ford car or the like, so as to allow 15 access to the valve, and having a portion adapted to abut against the block below the valve spring, said device being provided with a pivoted valve spring engaging and holding member and a cam lever for operating and locking said last described member.

With these and other objects in view, my invention consists in the construction, arrangement and combination of the various parts of my device, whereby the objects contemplated are attained, as hereinafter more 25 fully set forth, pointed out in my claims, and illustrated in the accompanying drawings, in which:

Figure 1 shows a vertical sectional view 30 through an engine block, having my valve spring lifter installed thereon, one of the upper arms of the tool being shown in section.

Figure 2 shows a perspective view of my 35 valve spring lifter; and

Figure 3 shows a detailed, sectional view taken on the line 3—3 of Figure 1.

One of the great purposes of my invention is to provide a valve spring lifter having its 40 parts so constructed and arranged that the device may be quickly and easily installed in position and manipulated for raising the valve spring and left in its installed position with the parts locked for holding the valve 45 spring raised.

The device, which I have constructed for accomplishing this purpose, comprises what I may call a main body, indicated in the accompanying drawings at A, and comprising 50 preferably two strips of metal, indicated by the reference character 10, fastened together by screws or the like 11^a, having generally the form of a large C, as shown for instance in Figure 1.

At its upper end, the free ends of the 55 strip 10 are spread apart, forming the por-

tions 11, which are adapted to rest on the top of the engine block 12 on opposite sides of a valve 13.

The strips 10 at their lower portions are 60 inclined downwardly and are spread apart, as shown in Figure 2, and at their extreme lower ends are again brought together and fastened by means of a screw or the like 11^a, such as those already mentioned. 65

Pivoted between the strips 10, where they are separated and spread apart is a lifting arm 14, one end of which projects forwardly and the other rearwardly from the strips 10, as illustrated in Figures 1 and 2. 70

The forward end of the lifting arm 14 has the bifurcated fingers 15. Pivoted between the strips 10 above the other end of the arm 14 is a cam 16, extending away from which is an arm or lever or handle 17. 75

The parts are so arranged that in the actual use of the valve spring lifter, the two members 11 are placed in position on the top of the engine block 12, after the head has been removed. The members 11 are 80 placed in such position as to straddle the valve 13.

The fingers 15 are slid in under the valve spring 18 and the lower ends of the strip 10 are placed against the sides of the engine block, as illustrated in Figure 1. 85

The device is then supported in three points and is readily and easily held in position.

The device is thus installed with the arm 17 in the position shown in Figures 1 and 2, extending upwardly. The arm 17 is then lowered to its dotted line position shown in Figure 1, whereupon the cam 16 will engage and force downwardly the rearward end of 90 the arm 14, thus raising the fingers 15 and compressing the spring 18, whereupon the pin 19 in the valve stem will be readily accessible, so that it can be removed for permitting the removal of the valve and its 95 stem 20. 100

The members 11 are so arranged spaced on opposite sides of the valve and inclined away therefrom, as to permit the manipulation of the valve on its seat, without any interference on the part of the valve spring lifter with the grinding tool or the like. 105

When the valve has been repaired or replaced or ground, the pin 19 is replaced, and the arm 17 raised to permit the fingers 15 to 110 lower until the valve spring washer 21 rests against the pin 19, whereupon the valve

spring lifter may be readily and easily removed.

The device is readily supported in position because of its three point engagement with the engine block. This makes it easy to raise the spring without any slipping on the part of the valve spring lifter.

Two of the points of the suspension being on top of the engine block, there is no danger of the device slipping off accidentally.

It will be noted that the cam 16 is so arranged that it will move over center when manipulated to carry it from locking to unlocking position or vice versa.

Some changes may be made in the details of the construction of my improved valve spring lifter without departing from the real spirit and purpose of my invention, and it is my intention to cover by my claims, any modified forms of structure or use of mechanical equivalents, which may be reasonably included within their scope.

I claim as my invention:

25 1. A valve spring lifter comprising a main portion having a body portion of substantially the form shown, and provided at its

upper portion with diverging inclined arms, adapted to rest on top of an engine block, and at its lower portion with a part adapted to engage the side of the engine block, an arm pivoted to said body portion near the lower part thereof provided at one end with bifurcated fingers, a cam pivoted to said body portion and adapted to coact with the other end 30 of said arm for raising said fingers for lifting the valve spring, said cam being arranged to move passed center when manipulated to the limit of its movement in either direction.

2. A valve spring lifter comprising a pair 40 of strips secured together in substantially the form of a C, as shown, said strips being diverging at their upper ends and adapted to rest on top of an engine block and being spread apart for a portion of their length 45 near their lower ends, the lower ends of said strip being adapted to engage the side of an engine block, an arm pivoted between the strips near their lower ends, having bifurcated fingers at one end, a cam pivoted above 50 the other end of said arm between said strips and adapted to elevate the fingers, and an arm on said cam.

CLIFFORD C. YOUNG.
